[57] ABSTRACT

[21] Appl. No.: 301,217

[52] U.S. Cl. .... 52/758 H, 403/401

A method for sealingly connecting two identical sections of a door frame or the like one adjoining the other at a mitre-angle of 45°, the clamping means for drawing the adjoining flanges of the profiled sections one to the other being clamped between abutments provided on said flanges and the webs of the profiled sections adjoining each other at the mitre-joint, a part of said clamping means extending over the webs.

SEAL JOINT BETWEEN TWO IDENTICAL PROFILED SECTIONS AND THE ASSOCIATED MITRE-JOINT CONSTRUCTION

DISCUSSION OF THE PRIOR ART

The invention relates to a method for making a seal joint between two identical profiled sections for example of a door frame, one adjoining the other at a mitre-angle of 45°, each profiled section consisting of a web and at least one flange making an angle with said web. 10

The known method is disadvantageous in this way that the joint between the adjoining webs of the profiled section is not sealed exactly, whereas it is of great advantage for the appearance of the frame or the like to be formed from the profiled sections to seal said joint very exactly, in particular when finally the profiled sections should be finished by applying thereon an electrostatic spray of powder. 15

SUMMARY OF THE INVENTION

It is an object of the invention to provide a method for sealingly connecting two identical profiled sections of a door frame or the like one adjoining the other at a mitre-joint of 45°, each profiled section including a web and at least one flange making an angle with said web. 20

This object is obtained according to the invention in that the clamping means for drawing the adjoining flanges of the profiled sections one to the other is clamped between abutments provided on said flanges and the webs of the profiled sections adjoining each other at the mitre-joint, a part of said clamping means extending over the webs. 25

It is a further object of the invention to provide a method for sealingly connecting two identical profiled sections of a door frame or the like each section having two flanges in that the clamping pressure of the clamping means between the flanges and the webs of the profiled sections is transmitted via a resilient cover-member extending along the entire length of the mitre joint between said webs. 30

The invention also provides a mitre-joint construction for carrying out the method according to the invention, said mitre-joint construction comprising clamping means adapted to be arranged on flanges of profiled sections adjacent the joint said clamping means comprising a flat clamping plate having at one end a recess profiled in accordance with the angle between the webs of the profiled sections at the mitre-joint, the other end of said plate being provided with another recess for engaging cams disposed on the said flanges of the profiled sections, so that the clamping plate can be placed in respect of the plane of the flanges in an oblique direction between the webs and the cams, whereupon by driving the flat clamping plate as close to the plane of the flanges as possible the said plate is clamped between the webs and the cams, whereby the mitre-joint between the flanges as well as the mitre-joint between the webs is sealed. 35

When the mitre-joint is used for interconnecting two profiled sections each comprising two flanges, two flat clamping plates are required to interconnect each set of flanges and the plates can, advantageously, be combined with a resilient cover-member engaging a marginal section of each web at the mitre-joint between the webs of the profiled sections, the profile of the first

mentioned recess corresponding to at least that part of the outer surface of the cover-member covering the joint.

As a result the cover-member is gripped at its upper and lower end by a clamping plate, and thus the entire length of the flanges of the cover member press against the webs of the profiled sections, which consequently further enhances uniform sealing of the longitudinal joint between said webs over the entire length thereof. 10

Moreover it is possible to apply the present invention to two profiled sections each of which is provided with one flange only, only one flat clamping plate being employed together with a resilient cover member the cover member being fixed at one end by the clamping plate, the remainder of the cover plate resting loosely on the marginal sections of the webs adjacent the mitre-joint. The cover-member preferably consists of two flanges interconnected one with the other by means of a convex ridge extending longitudinally thereof. With this embodiment the or each clamping plate can be more securely engaged with the cover-member and the resilient properties of the cover member are employed more usefully. 15

SURVEY OF THE DRAWINGS

FIG. 1 shows, partly in section, a finished mitre-joint construction between two profiled sections according to FIG. 2, the connecting means provided on the profiled sections shown thicker as in reality for the sake of clarity. 20

FIGS. 2 and 3 show respectively a sectional view along the lines II-II and III-III respectively, in FIG. 1, on a larger scale. 25

DESCRIPTION OF PREFERRED EMBODIMENTS

Referring to the drawings identical profiled sections 1 and 1a of, for instance, a door frame adjoin each other by a mitre-joint 2 at an angle of 45°. A plate 5 is secured to a flange 3 of the section 1 (see FIG. 1) by spotwelded joints 4 and a plate 6 is secured to the non visible flange of the section 1a also by means of spotwelded joints 4. The plates 5 and 6 lie flat on the flanges except their end edge sections 5a and 6a, respectively, of which end sections are of reduced width and are engaged between cams 7, 7' and 7a, 7a', respectively, provided at appropriate locations on the related flange. In this way there are formed cavities enabling the profiled section to be suspended by means of one or more hooks during manufacturing thereof. 30

The adjacent edges of the plates 5 and 6 at the mitre-joint 2 are provided with teeth 8 and 9 respectively, which teeth mesh exactly when the profiled sections 1 and 1a are mitred together, the intermediate space shown between the teeth being shown in the drawing only for clarity (see FIG. 2). The teeth 8 and 9 prevent relative movement of the sections 1 and 1a. Each plate 5 and 6 respectively is provided with a cam 10 and 10a, respectively, arranged so that when the profiled sections 1 and 1a adjoin each other the cams 10 and 10a are situated on a line perpendicular to the mitre-joint 2 and symmetrically on either side of said joint. A simple clamping plate 11 having legs 13 and 13a, extending from one side thereof and defining a recess 12 therebetween and a recess 14 on the opposite side. The clamping plate 11 is adapted to be clamped in a flat position on the flanges of the profiled sections 1 and 1a 35

with the cams 10 and 10a located in the recess 12 and engaged by legs 13 and 13a respectively and with a curved ridge 15 of a cover-member 16 received in the recess 14. The cover member 16 has flanges 17 and 17a engaging the corresponding webs 18 and 18a of the profiled section 1 and 1a, respectively. The cover member 16 extends in the longitudinal direction along the mitre-joint 2 between the webs 18 and 18a as far as the second flanges of the profiled sections 1 and 1a, only the second flange 19 of the section being visible in FIG. 1.

Plates 20 and 20a, are secured by spotwelded joints 4 to the said second flanges 19 of the profiled sections 1 and 1a, in the same way as plates 5 and 6 are secured to flanges the plates having end edge sections 21 and 21a, respectively, of reduced width engaged between cams 22, 22' and 22a, 22a' respectively. Said plates 20 and 20a provided with cams 23 and 23a, and teeth 24 and 25, said teeth being respectively adapted to mesh in the same way as the teeth 8 and 9 in plates 5 and 6. 20

A clamping plate 26 corresponding to plate 11 is provided in order to lock the flanges 19 sealingly together on the mitre-joint 2. The plate 26 includes legs 28 and 28a, defining a recess 27 therebetween, a recess 29 being formed on the side of the plate 26 remote from recess 27. The clamping plate 26 is adapted to be clamped flat on the flanges 19 with the cams 23 and 23a located in the recess 27 and engaged by the legs 28 and 28a and with the recess 29 receiving the curved ridge 15 of the cover-member 16 already mentioned, the flanges 17 and 17a of said cover-member engaging the corresponding webs 18 and 18a of the profiled sections 1 and 1a, respectively.

The effect is that each clamping plate 11 and 26, 35 when in position not only draw their corresponding flanges 3 of 19 of the profiled sections 1 and 1a one towards each other, thus sealing the mitre-joint 2 at the location of said flanges but, due to the tension produced in the clamping plates, the cover-member 16 is, at its upper and lower end, firmly pressed, via the ridge 15 and the flanges 17 and 17a against the webs 18 and 18a of the profiled sections 1 and 1a, respectively. This effect is further intensified when the cover-member 16 consists of a material with slightly resilient properties, 40 but which is mechanically rigid to such an extent that under the influence of the pressure exerted on its upper and lower end, its flanges 17 and 17a, respectively, engage firmly the webs 18 and 18a of the profiled section 1 and 1a, respectively. As a consequence also the mitre-joint 2 extending between the webs 18 and 18a

is sealed without providing any additional means on said webs. The slightly resilient cover-member 16 also retains the clamping plates 11 and 26, in their clamped position because the counter pressure of the cover-member 16 urges the clamping plates towards the cams 13, 13a, and 23, 23a, respectively.

Obviously many modifications as to details of the additional means to interconnect the profiled sections are possible within the scope of the invention, as defined by the appendent claims while the mitre-joint construction can also be applied to profiled sections having one flange only.

What I claim is:

1. A mitre-joint construction comprising, two identical profiled sections of a door frame or the like, one adjoining the other at a mitre-angle of 45°, each profiled section including a web and at least one flange making an angle with said web, a cam fixed on each of said flanges, clamping means arranged on said flanges of profiled sections adjacent the joint, said clamping means comprising a flat clamping plate having one end profiled generally in accordance with the angle between the webs of the profiled sections at the mitre-joint, the other end of said plate being provided with a recess defined by edges which are engaged by said cams disposed on the said flanges of the profiled sections so that the clamping plate can be placed in respect of the plane of the flanges in an oblique direction between the webs and the cams, whereupon by driving 30 the flat clamping plate as close to the plane of the flanges as possible, the said plate is clamped between the webs and the cams, whereby the mitre-joint between the flanges as well as the mitre-joint between the webs is sealed.

2. The construction set forth in claim 1 including a flat plate rigidly secured to each of said flanges, said plates having adjacent edges and interengaging teeth along said edges to permit interengagement between said plates and consequently prevent relative movement between said sections.

3. The construction as claimed in claim 2 including a resilient cover member engaging the webs of said sections at said mitre-joint, said one end of said clamping plate abutting against said cover member to urge said cover member firmly against said webs.

4. A mitre-joint construction as claimed in claim 3 further characterized in that said cover member comprises two flanges interconnected together by means of a convex ridge extending longitudinally thereof, said 50 clamping plate abutting against said convex ridge.
